SKATE

Leon Dewan and John Bartho, New York, N. Y., assignors, by mesne assignments, of sixteen per cent to Leon Dewan, fifteen per cent to John Bartho, fifteen per cent to Joseph R. Wren, seventeen and one-half per cent to Frank Conlan, fifteen per cent to Herbert C. Roemer, five per cent to Hamilton E. Smith, four per cent to John J. O'Brien, and twelve and one-half per cent to James H. Wren, stockholders of Lucky Brakes, Inc., a corporation of New York

Application September 7, 1937, Serial No. 162,716

7 Claims. (Cl. 280—11.20)

This invention relates generally to roller skates and more particularly to braking mechanism therefor and is an improvement over the invention described and claimed in our Letters Patent Number 2,080,766.

It is a primary object of our invention to prevent accidents in the use of roller skates.

It is another object to readily stop or retard the movement of roller skates.

10 It is still another object to provide braking mechanism for roller skates that may be readily mounted on the ordinary standard type of roller skate without any modification of such skate.

15 It is still another object to provide a braking mechanism for roller skates that is shock proof in use.

Yet another object is to provide a braking mechanism that can readily be repaired and replaced.

20 It is a further object to provide a braking mechanism for roller skates that is simple and rugged in construction and economical to manufacture.

The foregoing and other objects and advantages of the present invention will be apparent 25 from the description thereof to follow taken in connection with the accompanying drawing in which—

Figure 1 is a side view of a roller skate with one of the rear wheels removed to show the improved braking mechanism.

Figure 2 is a side view with the rear end tilted to show the improved braking mechanism in operative position.

Figure 3 is a rear end view of the skate.

35 Figure 4 is a perspective view of the improved braking mechanism.

Figure 5 is a detail view partly in section showing the mounting of the braking mechanism.

The present invention is illustrated as applied 40 to an ordinary type of roller skate 10 having a foot supporting member 11, front wheels 12 and rear wheels 13. The rear wheels are removably mounted as usual on an axle 14 and are fastened thereto by nuts 15. The rear axle is supported in 45 a saddle or housing 16 which also supports a rubber block 17 leaving the sides thereof uncovered. The saddle 16 is suspended from a bracket 18 fastened to the under side of the foot supporting member 11.

50 The improved braking unit 19 is detachably mounted on the rear axle 14 at each side of the saddle 16 and block 17. This braking unit comprises a metal arm or shank 20 having an opening 21 adjacent one end. The other end of the 55 arm is formed with an integral flange 22 disposed

at right angles to the arm. This flange has a screw threaded bolt or stud 23 fastened thereto and extending outwardly thereof. A friction member or brake shoe 24 of metal is supported on the flange. The brake shoe 24 consists of a 5 thick body portion 25 and a slimmer slotted portion 26 disposed at a right angle to the body portion. When mounted on the flange 22, the body portion of the brake shoe extends outwardly in the same plane as the plane of the arm 20, and 10 the slotted portion extends in the same plane as the plane of the flange 22. A nut 27 removably fastens the brake shoe on the threaded bolt 23, and a washer 28 may be mounted on the bolt 15 between the nut and slotted portion of the brake 15 shoe.

The free end of the arm 20 terminates in an inclined lug 29 and formed integrally on the upper edge of the arm at a point approximately in line with the opening 21 is a lug 30. 20

In assembling the rear portion of the skate, a braking unit is mounted on the rear axle 14 at each side of the rubber block 17 by inserting the rear axle 14 through the opening 21 of the arm. The arm is then moved into close contact with 25 the side of the rubber block 17. A rear wheel is mounted on the axle and moved into contact with the arm 20 of the braking unit. This arm is adjusted or positioned on the rear axle so that the brake shoe body portion 25 is positioned above 30 the ground or other supporting surface as shown in Fig. 1. A nut 15 is threaded onto the outer end of the rear axle and tightened to clamp the arm 20 of the braking unit between the rear 35 wheel and rubber block so that the terminal lug 29 bites into the side of the rubber block and tends to hold the braking unit in adjusted position and prevents relative movement between the parts. When in proper position, the upper lug 30 is underneath and in snug contact with the 40 floor or base 32 of the saddle 16.

In operation when it is desired to retard or stop the movement of the skate, all that it is necessary to do is to slightly tilt the rear end of the skate rearwardly and downwardly as shown in Fig. 2. 45 The shape of the brake shoe is such that this tilting action will cause the entire bottom of the brake shoe to frictionally engage the ground as shown in Fig. 2 and depending on the pressure exerted will retard or stop the movement of the 50 skate as desired.

The slot and stud connection between the arm 20 and brake shoe permits adjustment of the brake shoe up and down as desired.

When the brake shoes are in frictional engage- 55

ment with the ground, they and the rear wheels provide a four point engagement with the ground making it difficult for the feet or legs of the skater to accidentally fly out from under him.

5 Also when the skate is in tilted position, the weight of the skater is transferred to the lug 30 and any shock caused by the braking action is absorbed by the rubber block 17.

10 The free front end of the brake shoe may be made thicker than the remainder of the shoe so that it will stand greater wear at such point.

15 It has been found in practice that an individual using these skates may stop not only by putting one foot forward and tilting the skate to cause frictional engagement with the ground, but may even remove the other foot from the ground and rest entirely upon the tilted skate thereby causing a greatly increased braking action since the whole weight of the body is applied to the braking

20 skate. However, the body weight is still divided between the rear wheels and the brake shoes.

25 In order to further increase the portion of the body weight applicable to the brakes, the brake shoe bottom is placed as closely as possible to the vertical plane of the axle so that the leverage obtained is greater. In view of the fact that a lever is formed with the rear axle as a fulcrum, the front part of the foot as the point of power application, and the heel as the moved body, the 30 ease of rising and tilting the skate is increased and more of the weight of the body can be made to rest on the brake shoes than on the rear wheels and thereby increase the braking action.

35 The brake shoes are positioned behind the rear wheels for the following reasons: Under most outdoor conditions a certain unevenness of the ground often causes the part between the wheels to be higher than where the rims are riding. It is evident that the brake bottoms must be placed 40 quite low in order not to necessitate too great a tilting of the skate and thus in the above mentioned case the possibility often arises of the brake suddenly engaging such an obstacle at high speed with consequent injury. However, according to the present invention the wheels, themselves, rise over any ground irregularities and carry the brakes upwardly with them. Furthermore any small stones, etc. that might otherwise engage the brake shoes are thrown to one side by 45 the advancing wheels.

50 Changes in details might be resorted to without departing from the principle of the invention and we desire therefore to be limited only by the prior state of the art and the appended claims.

55 We claim:

1. As an article of manufacture, a braking unit for roller skates comprising an arm having an opening for receiving an axle, an integral flange formed at one end of the arm, a brake shoe detachably and adjustably mounted on said flange, a lug at the opposite end of the arm and a second lug on the arm at a point between the flange and first lug and disposed at an angle to the plane of the arm.

2. As an article of manufacture, a braking unit for roller skates comprising an arm having an opening for receiving an axle, a flange formed at one end of the arm, a brake shoe detachably and adjustably mounted on said flange, a lug 5 formed at the opposite end of the arm, a second lug formed on the arm between the flange and first lug, and a slot and stud connection between the flange and brake shoe for detachably and adjustably fastening the flange and brake shoe. 10

3. In a roller skate, a saddle member, an axle supported by said saddle, a rubber block supported by said saddle, a braking unit detachably and adjustably supported on the axle at each side of the saddle, means on each unit adapted to co-operate with said rubber block for holding the unit in adjusted position and means on each unit adapted to cooperate with the saddle for supporting 15 the weight of the skater.

4. In a roller skate, a saddle member, an axle supported by said saddle, a rubber block supported by said saddle, a braking unit detachably and adjustably supported on the axle at each side of the saddle, a lug on each unit adapted to co-operate with said rubber block for holding the unit in adjusted position and means on each unit adapted to cooperate with the saddle for supporting 20 the weight of the skater. 25

5. In a roller skate, a saddle member, an axle supported by said saddle, a rubber block supported by said saddle, a braking unit detachably and adjustably supported on the axle at each side of the saddle, means on each unit adapted to cooperate with said rubber block for holding the unit in adjusted position and a lug on each unit adapted to cooperate with the saddle for supporting 30 the weight of the skater. 35

6. In a roller skate, a saddle member, an axle supported by said saddle, a rubber block supported by said saddle, a braking unit detachably and adjustably supported on the axle at each side of the saddle, a lug on each unit adapted to cooperate with said rubber block for holding the unit in adjusted position and a second lug on each unit adapted to cooperate with the saddle for supporting 40 the weight of the skater. 45

7. In a roller skate, a saddle member, an axle supported by said saddle, a rubber block supported by said saddle, a wheel on said axle outside of and at each side of said saddle, a braking unit between each wheel and side of the saddle, each unit comprising an arm on said axle, a lug on one end of said arm in biting engagement with the rubber block, a second lug on said arm in snug engagement with the saddle, a flange at the other end of the arm, a brake shoe on the flange, a slot and stud connection between the flange and brake shoe and means for clamping the braking units between the wheels and rubber block and saddle. 50 55
